UNITED STATES PATENT OFFICE.

SAMUEL JUDSON BALLARD, OF LOS ANGELES, CALIFORNIA, ASSIGNOR OF THREE-FOURTHS TO CALVIN W. BROWN, OF LOS ANGELES, CALIFORNIA.

APPLIANCE FOR SOUND-TRANSMITTERS.

SPECIFICATION forming part of Letters Patent No. 740,512, dated October 6, 1903.

Application filed May 14, 1900. Serial No. 16,677. (No model.)

To all whom it may concern:

Be it known that I, SAMUEL JUDSON BALLARD, a citizen of the United States, residing at Los Angeles, in the county of Los Angeles and State of California, have invented a new and useful Appliance for Sound-Transmitters, of which the following is a specification.

My invention is applicable for the earpiece or the mouthpiece of sound-transmitters, such as telephones and other appliances for transmitting the tones of the human voice, and is designed to form a protection for the interior of the mouthpiece or earpiece to which it is applied and also to afford protection to the user against any danger of infectious or contagious diseases which might be transmitted from effluvia deposited in the mouthpiece or earpiece by a previous user.

My invention comprises the combination with a sound-transmitter of a shielding-strip and means for slidably holding said strip across the mouth of said transmitter, so that instead of the mouth of the transmitter being presented to the mouth or ear of the user the shielding-strip will be interposed between the mouth of the transmitter and the mouth or ear of the user, as the case may be, and the subsequent user may remove the strip and any effluvia or impurities of any kind which may be thereon by drawing the strip to bring a fresh portion of the shielding-strip in front of the mouth of the mouthpiece or earpiece and then tearing off the portion of the paper which has previously been used.

A further object of my invention is to provide a superior, desirable, and attractive advertising medium in connection with telephones and in the practical operation of my invention to offer an inducement for keeping a constant supply of the hygienic shielding-strip for use with the telephone.

Another object of my invention is to provide a convenient memorandum appliance for telephone users.

My invention may be embodied in various forms and parts of it may be permanently formed with the main body of the mouthpiece or earpiece of the transmitter. It may also be formed as an attachment which will

be independent of the transmitter and can be readily applied thereto by a clamp or otherwise. It is not necessary for a thorough understanding of my invention that all the forms in which it may be embodied be shown.

The accompanying drawings illustrate my invention in one of the modes in which it may be carried out.

Figure I is a perspective view of my newly invented appliance on a telephone sound-transmitter. Fig. II is a side elevation of the same. Fig. III is a plan view of the same. Fig. IV is a section on line IV IV, Fig. III. Fig. V is a perspective view of the attachment detached. The shielding-strip is broken for clearness of illustration.

a indicates a sound-transmitter.

b indicates a shielding-strip, which is preferably made of paper and may be furnished with advertisements (not shown) arranged at suitable intervals. The strip is preferably commercially supplied in the form of a roll of paper slightly wider than the transmitter-mouth *a'* and suitably retained at one side of said mouth, preferably at the rear of the left side, by a roller *c*, so that the paper may be drawn across said mouth, thus presenting a perfectly fresh surface for the user, and may be torn off after use. After pulling the paper across the mouth of the transmitter for a few inches the user knows that no other person has used or breathed onto the surface that he is about to use. This is considered important from a hygienic standpoint, and the mechanism of the telephone is protected from the moisture caused by the breath of the users and from dust, and consequently should work better and longer without attention from telephone inspectors. The paper can be utilized for advertising purposes, a few words (not shown in the drawings) being printed thereon at regular intervals, so that the advertisement appears in front of the mouth of the transmitter before the user, and another advertisement will appear as the paper is drawn forward and torn off.

Any suitable means may be furnished for slidably holding the strip across the mouth of the transmitter, and preferably a suitable ten-

sion device is provided at the side of the mouth of the transmitter opposite to the side from which the paper strip is fed to slidably hold the strip across said mouth. For this purpose in the drawings I have shown a bearing *d* at the side of the transmitter-mouth opposite the side at which the paper-roll or other strip-supplying means is located, and said shielding-strip *b* extends across said mouth and behind said bearing. Preferably the bearing is rearward of the mouth of the transmitter, so that the shielding-strip will be drawn forward from the strip-supplying means, then bent down across in front of the mouth, and then back behind the bearing, thus holding the strip taut across the mouth of the transmitter. Suitable means are provided for holding said strip against said bearing to prevent any withdrawal of the strip by resiliency. *e* indicates a tension-roller for this purpose.

f indicates a spring to throw the tension-roller *e* against the bearing *d*. The bearing *d* may be of any suitable form. When the bearing and tension device are rollers, as indicated in the drawings, the shielding-strip is gripped between said rollers.

g indicates an edge piece, against which the free end of the strip may be drawn in order to tear it from the body of the strip.

h indicates a tablet over which the strip may be drawn and which forms a support for the strip, so that the users of the telephone may conveniently use the paper strip for the purpose of making memoranda thereon.

When the appliance is manufactured separately from the transmitter to be applied as an attachment to the transmitter, a clamp *i* is provided, and the strip-roller *c* or other means for supplying the shielding-strip to be drawn across the mouth of the transmitter and the means for holding the strip tight across the transmitter-mouth will be carried by said clamp.

In the drawings I have shown means in front of the transmitter-mouth for holding the strip against said mouth. Such means consist in a spring-pressed ring *j*, which is preferably the same diameter as the mouth-piece. The said ring is preferably pivoted to the clamp-frame and is pressed by a spring *k*.

l indicates a nut on the shaft-roller *c*, whereby the roller for holding the roll of paper is detachably attached to the clamp-frame.

In practical use the appliance will be furnished with a strip of paper placed on the roller, as indicated in the drawings, and the free end of the strip will be brought down in front of the mouthpiece or earpiece of the transmitter, and when the user desires to bring an unused portion of the paper across the mouth of the transmitter he will grasp the free end of the paper and draw it up against the edge piece *g* and will tear off a portion of the paper and throw it away or otherwise dispose of it. If he desires to make any memorandum on the paper, he will do so before tear-

ing it off, using the tablet *h* to support the paper against the pressure of the pencil.

The ring *j* may be detached and dispensed with, if desired, thus to present to the user only the face of the strip in front of the transmitter-mouth.

The nut *l* when screwed home holds the roller friction tight to prevent racing of the strip.

The strip pressing roller *e* and the roller *d*, together with the strip-feeding appliance, holds the strip taut in front of the speech appliance *a* in the usual operation of the device; but the means *j*, directly in front of the speech appliance, serves to hold the strip flat against the rim of said appliance to prevent buckling up in case the strip should become disengaged from the lower roller or should the upper roller be unreeled too much.

What I claim, and desire to secure by Letters Patent of the United States, is—

1. The combination with a sound-transmitter, of means at one side of the mouth of said transmitter for supplying a shielding-strip to be drawn across said mouth; means at the other side of said mouth for holding said strip across said mouth; and a tablet over which said strip may be drawn. 95

2. An attachment for sound-transmitters comprising a clamp to clamp upon the transmitter; means carried by said clamp for supplying a shielding-strip to be drawn across the mouth of the transmitter; and means carried by said clamp for holding the strip across the transmitter-mouth. 100

3. An attachment for sound-transmitters comprising a clamp to clamp upon the transmitter; means carried by said clamp for supplying a shielding-strip to be drawn across the mouth of said transmitter; a bearing for said strip; and a spring-pressed roller for holding said strip against said bearing. 105

4. The combination with a sound-transmitter, of a tearable strip; means for slidably holding said strip across the mouth of the transmitter; and a tablet to the rear of said strip and across which the strip may be drawn. 110

5. The combination with a sound-transmitter, of a tearable strip; means for slidably holding said strip across the mouth of the transmitter; an edge piece across which the free portion of the strip may be drawn to be torn; and a tablet to the rear of the strip and across which the strip may be drawn, said tablet being between the transmitter and the edge piece. 115

6. An attachment for speech appliance comprising means for engaging with said appliance and provided with mechanism for holding a shielding-strip in front of the appliance, and means directly in front of the appliance for holding the strip against outward movement. 125

7. An attachment for speech appliance, comprising means for engaging with said appliance and provided with mechanism for holding a shielding-strip in front of the appli- 130

ance, and yielding means directly in front of the appliance for holding the strip against outward movement.

8. An attachment for speech appliance, comprising means for engaging with said appliance and provided with mechanism for holding a shielding-strip in front of the appliance, and a ring in front of the appliance for holding the strip against outward movement.

9. An attachment for speech appliance, comprising means for engaging with said appliance and provided with mechanism for holding a shielding-strip in front of the appliance, and a ring yieldingly held in front of the appliance for holding the strip against outward movement.

10. An attachment for speech appliance, comprising means for engaging with said appliance and provided with mechanism for holding a shielding-strip in front of the appliance, and a ring hinged at one side in position to be swung in front of the attachment and hold the strip against outward movement.

11. An attachment for speech appliance, comprising a frame for engaging with said appliance and provided with mechanism for holding a shielding-strip in front of the appliance, and a spring-pressed ring hinged to the frame in position to be swung over in front of the appliance and hold the strip against outward movement.

12. An attachment for speech appliance, comprising a frame for engaging with said appliance and provided with mechanism for holding a shielding-strip in front of the appliance, a tablet, and an armed ring hinged to the frame in position to be swung in front of the appliance with the arms extending across the tablet.

13. An attachment for speech appliance, comprising a frame for engaging with said appliance, a strip-roll at one end of the frame and clamping-rolls at the other, a tablet adjacent to the clamping-rolls, and a ring hinged to the frame adjacent to said rolls in position to be swung across the tablet and lie in front of the appliance and prevent outward movement of the strip.

14. An attachment for a speech appliance, comprising, means for engaging with said appliance and provided with mechanism for holding a shielding-strip taut in front of the appliance and means in front of the appliance for holding the strip against outer movement.

In testimony whereof I have signed my name to this specification, in the presence of two subscribing witnesses, at Los Angeles, California, this 18th day of April, 1900.

SAMUEL JUDSON BALLARD.
